ABSTRACT OF THE DISCLOSURE

A phase shifter circuit having two ports of a directional coupler coupled to two ports of a hybrid junction through two variable attenuators arranged to introduce attenuation in the coupled paths. An alternating signal introduced in a third port of the directional coupler results in voltages at the remaining two hybrid junction ports, one voltage advanced and the other retarded in phase through angles controlled by the attenuators.

Background of the invention

This invention relates to electric phase shifters and more particularly to phase shifters which may be electrically controlled at very rapid rates.

It is sometimes necessary to derive from an input signal two voltage vectors which are shifted in phase in opposite directions with reference to the input signal. An example of such a use is found in monopulse phased array radar applications which require a convenient means for rapidly varying the phase angles of two voltage vectors. These are applied to the sum and difference channels of the radar to facilitate beam steering. Heretofore, phase shifters having reactive components have been used in each array element for this purpose but, because they involve reactive components, they are frequency sensitive. The phase angle can be held more nearly constant over a wide frequency band if reactive elements can be avoided.

Summary of the invention

The phase shifter of this invention comprises a circuit having two ports of a directional coupler coupled to two ports of a hybrid junction through two variable attenuators arranged to introduce attenuation in the coupled paths. These attenuators should be substantially free of reactance and they may either be independently adjustable or they may be ganged for simultaneous adjustment. An alternating signal introduced in a third port of the directional coupler results in output voltages at the remaining two hybrid junction ports, one output voltage advanced and the other retarded in phase through angles controlled by the attenuators. If the attenuators are ganged to simultaneously introduce attenuation in their respective paths and the voltage transmission coefficient for one attenuator is made proportional to the sine and the coefficient of the other attenuator proportional to the cosine of an arbitrary angle, the phases of the two output voltages will be shifted through this same arbitrary angle and in opposite directions with reference to the input signal.

Brief description of the drawings

The invention may be better understood by reference to the accompanying drawings in which:

FIG. 1 is a circuit diagram disclosing the essential features of an embodiment of the invention;

FIG. 2 is a vector diagram illustrating the phase relationships of the voltages at the several ports shown in FIG. 1; and

FIG. 3 is a fragmentary view of a conventional type of microwave attenuator suitable for the practice of this invention.

5 The directional coupler 12 shown in FIG. 1 should have a coupling coefficient equal to one-half the square root of two, thereby identifying this coupler with those known in the art as a 3 db directional coupler. Directional couplers suitable for the practice of this invention are disclosed in United States Patent 2,701,340 granted Feb. 1, 1955 to S. E. Miller and in an article by James K. Shimizu entitled "Strip-line 3-db Directional Couplers" published in the 10 1957 Institute of Radio Engineers Wescon Convention Record, vol. 1, part 1, pages 4-15.

15 Directional coupler 12 has four ports, 1, 2, 3 and 4 and hybrid junction 13 also has four ports, 5, 6, 7 and 8. Ports 3 and 4 of the directional coupler are coupled, respectively, to ports 5 and 6 of the hybrid junction through attenuators 10 and 11, attenuator 10 being included in the transmission path between ports 3 and 5 while attenuator 11 is included in the transmission path between ports 4 and 6. Port 2 of the directional coupler is connected to ground through an impedance 20 equal to the characteristic impedance of the coupler. It is assumed, of course, that all other ports also face impedances equal to the characteristic impedance. It is a property of directional couplers that a signal applied to the input port 1 will appear at port 3 without suffering any substantial phase shift but will be reduced in amplitude by a factor equal to the coupling coefficient. A signal will also appear at port 4 equal in magnitude to that appearing at port 3 but shifted in phase by 90 degrees. Under these conditions the voltage at port 2 will be zero. Attenuator 10 will change the magnitude of the voltage received from terminal 3 by a factor determined by the amount of attenuation it provides and will deliver this voltage to port 5 of the hybrid junction. Similarly, attenuator 11 will change the amplitude of the voltage received from port 4 before delivering it to port 6 of the hybrid junction. In accordance with the preferred embodiment of the invention, attenuators 10 and 11 may be ganged through linkage 9 so that attenuation may be simultaneously changed in both transmission paths. Also in accordance with the preferred embodiment of the invention, the voltage transmission coefficient provided by attenuator 10 will be made to vary as the cosine of an arbitrary angle α while attenuator 11 will be made to provide a voltage transmission coefficient in the lower transmission path proportional to the sine of the same angle. Alternatively, the ganging arrangement need not be used and the two attenuators may be independently adjusted at will to provide different phase shifts as desired. However, when the ganging arrangement is used, the voltages appearing at terminals 7 and 8 of the hybrid junction can be caused to shift in phase by equal amounts in opposite directions with reference to the voltage applied to input port 1 of the directional coupler.

55 To illustrate the circuit operation, it may be assumed that the input voltage V_1 applied to port 1 is $A \sin \omega t$ as shown in FIG. 1. This voltage is shown as vector V_1 in FIG. 2 at instant t with reference to axis 20. It is assumed that all of the vectors in FIG. 2 are rotating at the rate ω counterclockwise about the origin 0 so that at instant t vector V_1 will be at an angle equal to ωt . This will be recognized as a standard convention for vector diagrams. The than that of V_1 by the factor $1/\sqrt{2}$ and will be in phase amplitude of voltage V_3 appearing at port 3 will be less 65 with voltage V_1 as shown in the vector diagram. The voltage V_4 appearing at port 4 will have the same magnitude as voltage V_3 but will be retarded in phase with reference to voltage V_3 by 90 electrical degrees. For these reasons, voltage V_3 is represented as a sine function in FIG. 1 and voltage V_4 is represented as a negative cosine function. The voltage V_5 at port 5 will be in phase with voltage

V3 but will be reduced in magnitude by the voltage transmission coefficient of attenuator **10** which is, as indicated in FIG. 1, equal to the cosine of the arbitrary angle α . Correspondingly, the voltage **V6** at port **6** is in phase with the voltage **V4** at port **4** but reduced in magnitude by the voltage transmission coefficient of attenuator **11** which is, as indicated in FIG. 1, equal to sine α .

The voltages **V5** and **V6** at ports **5** and **6** combine vectorially in the hybrid junction **13** so as to produce a voltage **V7** at terminal **7** and voltage **V8** at terminal **8**, each at one-half the magnitude of the input voltage **V1**. Voltage **V7**, however, is retarded in phase with reference to the input voltage **V1** by the arbitrary angle α introduced by the attenuators **10** and **11** while voltage **V8** is advanced in phase by the same angle. These relationships are clearly shown in the vector diagram of FIG. 2. It will, therefore, be evident that as attenuators **10** and **11** are simultaneously adjusted to provide voltage transmission coefficients proportional, respectively, to the cosine and the sine of the arbitrary angle α , the phase relationships of voltage vectors **V7** and **V8** will increase and decrease with reference to the input voltage **V1** as the arbitrary angle α is increased and decreased. This is a necessary requirement in deriving voltages for the sum and difference channels of monopulse radar systems for beam steering purposes.

Attenuators **10** and **11** in FIG. 1 have been shown symbolically, using standard symbols for such devices. If the steering is to remain within the first quadrant, most any microwave attenuator may be used but where the angles are to be varied through all four quadrants the microwave attenuator must be arranged to not only introduce the variable voltage transmission coefficient but it must also be capable of reversing phase. While a perfectly useful device restricted for operation in one quadrant may be made, it is desirable in most modern radar applications that the attenuator be capable of operating in all four quadrants. An attenuator capable of this property is illustrated in FIG. 3 and is of the type disclosed in United States Patent 3,264,586 granted Aug. 2, 1966 to M. Rabinowitz.

FIG. 3 shows only one of the attenuators, for example, attenuator **10** of FIG. 1 which is connected between ports **3** and **5**. This attenuator employs a 3 db directional coupler of the same type as coupler **12** in FIG. 1. In comparing the directional coupler of FIG. 3 with coupler **12** in FIG. 1, it will be noted that ports **33** and **35** of FIG. 3 correspond with ports **1** and **2**, respectively, of FIG. 1, while the ports corresponding to ports **3** and **4** of FIG. 1 are shown in FIG. 3 as ports **34** and **36** terminated by variable resistors **31** and **32** having equal resistances **R**. These resistors preferably comprise PIN diodes which possess the property of changing their forward resistances as a function of a forward bias current. Port **33** is coupled via blocking capacitor **37** to input terminal **3** and port **35** is coupled via blocking capacitor **40** to output terminal **5**. Input terminal **3** and output terminal **5** of FIG. 3 are ports **3** and **5**, respectively, of FIG. 1. The diodes **31** and **32** are connected between their respective coupler ports **34** and **36** and the ground plane of the coupler represented by the conventional ground symbol **50**. The coupler shown is of conventional strip-line construction; one conductive path comprises arm **44** starting from port **33** and terminating in port **36** via arm **47** while the other conductive path comprises arm **45** starting from port **35** and terminating in port **34** via arm **46**. Coupling region **43** is common to both paths. The two paths are separated by a dielectric layer **48** and it is to be understood that additional dielectric layers, not shown, separate the two conductive paths from a surrounding ground plane, also not shown but symbolically represented by ground **50**. Bias current to the diodes is supplied in a conventional manner from current sources, not shown, connected to terminals **39** and **42** which are conductively connected to ports **33** and **35** via inductors **38** and **41**, respectively.

As is well known, if the resistances **R** of resistors **31** and **32** are made equal to the characteristic impedance of the coupler, there will be no reflections from their ports **34** and **36** so that energy entering at port **3** of FIG. 3 will not appear at port **5**. As these resistances are caused to differ from the characteristic impedance, the voltage appearing at port **5** will increase in magnitude and will reverse in phase as the resistances **R** are varied through the characteristic impedance of the coupler. When the resistances **R** are made zero, the voltage at port **5** will be out of phase with and about equal to the voltage at port **3** and as the resistances are caused to increase toward infinity, the voltage at port **5** will again approach the magnitude of the voltage at port **3** and will be in phase.

It will be evident to those skilled in this art that the invention is not limited to any particular kind of directional coupler providing it is arranged to have a coupling coefficient equal to $1/\sqrt{2}$ and that most any hybrid junction may be used providing it is capable of operating over the microwave band and to have the properties described above.

What is claimed is:

1. A microwave phase shifter comprising a directional coupler and a hybrid junction, each having four ports, a first transmission path coupling one of the directional coupler ports to one of the hybrid junction ports, a second transmission path coupling a second directional coupler port to a second hybrid junction port, an attenuator inserted in each transmission path so that an alternating voltage applied to a third port of said directional coupler will appear shifted in phase at the third and fourth hybrid junction ports by amounts controlled by the attenuators.

2. The combination of claim 1 wherein the attenuators in the two transmission paths are ganged for simultaneous operation.

3. The combination of claim 1 wherein the attenuator in one of said transmission paths is so constructed and arranged as to provide a voltage transmission coefficient proportional to the cosine of an arbitrary angle while the attenuator in the other transmission path is so constructed and arranged as to provide a voltage transmission coefficient proportional to the sine of the same arbitrary angle, and means coupling said attenuators together for simultaneous operation.

4. A microwave phase shifter comprising a directional coupler and a hybrid junction, each having four ports, a first transmission path coupling one of the directional coupler ports to one of the hybrid junction ports, a second transmission path coupling a second directional coupler port to a second hybrid junction port, means for connecting a third directional coupler port to a source of alternating voltage, and an attenuator means inserted in each of said transmission paths to simultaneously insert attenuation in said two paths so that the voltages appearing at the third and fourth hybrid junction ports will be simultaneously shifted in phase with reference to the voltage applied to said third directional coupler port.

5. The combination of claim 4 wherein said attenuator means provides a voltage transmission coefficient in said first transmission path proportional to the cosine of an arbitrary angle and in said second transmission path proportional to the sine of the same arbitrary angle so that the phases of the voltages appearing at said third and fourth hybrid junction ports will be shifted in opposite directions by equal angular amounts.

6. A microwave phase shifter comprising a directional coupler and a hybrid junction, each having four ports, a first transmission path coupling one of the directional coupler ports to one of the hybrid junction ports, a second transmission path coupling a second directional coupler port to a second hybrid junction port, an attenuator means inserted in each of said transmission paths to provide a voltage transmission coefficient in one path

in accordance with the sine of an arbitrary angle and to simultaneously provide a voltage transmission coefficient in the other transmission path in accordance with the cosine of the same arbitrary angle, whereby an alternating signal applied to a third port of said directional coupler will be advanced in phase by said arbitrary angle at a third port of said hybrid junction and retarded in phase by the same arbitrary angle at the fourth port of said hybrid junction.
